JACOB D. BUTLER, OF NORTHAMPTON, MASSACHUSETTS.

INTERLOCKED FLOORING.

1,334,222.

Specification of Letters Patent. Patented Mar. 16, 1920.

Application filed December 23, 1918. Serial No. 267,971.

To all whom it may concern:

Be it known that I, JACOB D. BUTLER, a citizen of the United States, and a resident of Northampton, in the county of Hampshire and State of Massachusetts, have invented a new and Improved Interlocked Flooring, of which the following is a full, clear, and exact description.

This invention relates to carpentry and 10 has particular reference to flooring of the block, mosaic, or parquet type.

Among the objects of the invention is to provide a high class parquet flooring that may be made and laid at much less expense 15 for material and labor than analogous floorings now being laid.

Another object of the invention is to provide flooring material made in uniform blocks or sections from small bits or scraps 20 of material which commonly are discarded or wasted.

Another object of the invention is to provide a sectional flooring that may be laid rapidly and with exactitude by anyone even 25 an unskilled workman.

A still further object of the invention is to provide interlocking flooring so designed and constructed as to enable a floor to be laid on any ordinary level surface, such as 30 a bed of concrete, without requiring nails or other hardware for holding or locking the parts or sections thereof in place.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views and in which—

Figure 1 is a fragmentary plan view 45 showing a partially laid floor in accordance with my invention.

Fig. 2 is an enlarged detail plan view partly in horizontal section showing more particularly the interlocking action of the 50 several blocks.

Fig. 3 is a transverse sectional detail on the line 3—3 of Fig. 2.

Fig. 4 is a broken longitudinal section on the line 4—4 of Fig. 2.

Fig. 5 is a vertical sectional detail approximately on the line 5—5 of Fig. 2, but

prior to the final adjusted position and showing especially the two different forms of grooves and the relation of the dovetailed tongue thereto.

Figs. 6 and 7 are respectively front and rear perspective views of the uniform blocks; and

Fig. 8 is a fragmentary detail view indicating the manner in which a block is put 65 into place.

For the purpose of the present illustrations and description it may be assumed that each of the standard blocks as a face area of exactly four by eight inches and with 70 tongues projecting from one end and one side a quarter of an inch requiring that the block from which the finished block is made must be four and a quarter by eight and a quarter inches. Also the half length blocks 75 must have a surface area of four by four with the original length or width of four and one quarter inches. I have found in my practice that the thickness of the finished block should be thirteen sixteenths of an 80 inch. I wish it to be distinctly understood, however, that while I have found the foregoing dimensions as entirely suitable for rapid and satisfactory work, any other suitable forms or dimensions within the scope 85 of my invention may be utilized.

Referring now more specifically to the illustrations each standard block indicated as a whole at 10, of perfectly rectangular form, is provided along one end which may 90 be regarded in this description as the left hand end with a groove 11 rectangular in cross section and having a depth of a quarter of an inch to receive the strong unbroken tongue 12 projected therein from the 95 next adjacent endwise disposed block, the length of which tongue is one quarter of an inch. Along the front side or edge 13 of the block are formed three dovetailed tongues 14, 15 and 16, the first having its 100 outer end lying flush with the bottom of the groove 11 while the last tongue 16 has its outer end flush with the end of the tongue 12 and hence being in effect an integral angular extension thereof. The tongue 105 15 at or near the center of the side edge 13 is preferably longer than either of the end tongues 14 or 16. The tongue 15 is equally spaced from both of the other two and the distance between them is slightly greater 110 than the length of the tongue 15. The rear side or edge 17 of the block is defined by a

plane perpendicular to the smooth finished top surface 18 and the bottom surface 19 of the block. This rear edge 17 is peculiarly mortised and dovetailed, there being provided two mortises 20 at about the centers of the end halves of the edge. Each mortise 20 is provided with parallel top and bottom walls, a flat bottom, and rounded ends. The dimensions of these mortises in cross section are somewhat greater than those of the tongues above described. (See Fig. 5). Between the two mortises 20 is provided a central dovetailed groove 21, and extending outward from the outer end of each mortise is another dovetailed groove, one at 22 merging into the end groove 11, and the other at 23 leading directly through the rear end of the end tongue 12. These dovetailed grooves 21, 22, and 23 are all in perfect alignment with one another along the longitudinal center of the rear edge 17. It will be appreciated from the foregoing description that any tongue of a block has in the same block its counterpart, the tongue 12 being opposite the groove 11, and the tongues 14, 15, and 16 being opposite the grooves 22, 21, and 23 respectively whereby in the assemblage of the blocks any groove will receive the counterpart tongue of the adjacent block and such two features will exactly fit each other.

In the practice of this invention after the floor support is laid whether it be of concrete or other material, the first operation of the workman is to scribe the floor in which operation he calculates the nearest true rectangle which includes multiples of eight inches in length and multiples of four inches in width, using for illustration the dimensions above indicated. The surplus floor space over this calculated rectangle is filled by means of scribing strips 24 and 25 fitted against the end and rear wall respectively of the room. These strips are provided respectively with tongues 12^a and 15^a, corresponding respectively with the tongues 12 and 15 of the blocks.

The strips 24 and 25 having been fitted and locked in place against the left end and rear wall by any suitable means in permanent position, the work of laying the blocks 10 is ready to proceed which may be done by any workman skilled or unskilled, and no mistake or fault can be made or result in so doing. The first block 10 in the rear left end corner is placed with its rear edge 17 directly against the strip 25 with its mortises 20 receiving the tongues 15^a of the strip. The block is then shoved or driven by a hammer or mallet to the left bringing the strip tongue 12^a into the end groove 11 of the block. The next block 10 may then be put in place in a similar manner against the strip 25 and forced to the left making interlocking engagement with the strip

tongues and the tongue 12 of the first laid block. The half blocks or fillers 10^a are constructed with counterpart tongues and grooves which correspond precisely with the tongues and grooves of the standard or master blocks 10 for the obvious purpose of making a complete floor as shown in Fig. 1, the several blocks of the floor breaking joints in a well-known manner.

The purpose of the mortises 20 will now be appreciated in that through them the edge tongues 14, 15, and 16 of any longitudinal series or combination of blocks will be received easily without forcing into such mortises. For example as shown in Fig. 8 one mortise 20 receives the adjacent tongues 16 and 14, and the other mortise 20 receives the tongue 15 of the same block that has the tongue 14 just mentioned. The block being set at this time is then moved to the left to interlock with the end tongue 12 at the left and to bring the tongue 15 at the left into the groove 22 and the contiguous tongues 14 and 16 into the central groove 21, and so on. The rounded ends of the mortises 20 facilitate the mating together of these interlocking counterpart tongues and grooves. The interlocking features, however, are so constructed that they possess a fairly snug or moderate driving fit.

I wish to call at this time particular attention to the combined tongues 12 and 16 at one corner of the block. Through this feature of construction the interlocking blocks possess wonderful strength and holding power and thereby there is no possibility for any roughness or unevenness of the floor to result either at the time it is laid or at any subsequent time.

While I have practised this invention extensively and satisfactorily, laying the blocks on concrete or other foundations without the use of nails or other hardware, except for the scribing strips, it is obvious that nails may be used if desired if the sub-floor is suitable, and for this purpose I manufacture the blocks with nail holes 26 through which nails may be driven if desired. After all the blocks are laid as above described, finishing scribing strips 115 having grooves to receive the exposed tongues along the right hand end and front edge of the flooring are set into place and fastened by any suitable means and thereby it is impossible for any portion of the floor 110 to lift, loosen, or separate whether nails are used through the blocks or not. Furthermore it is to be noted that the union between each block and all blocks or strips surrounding it is exceedingly strong, the 115 joint being locked approximately all the way along all ends and sides of the block. The bottom surface 19 of each block is preferably reduced forming a longitudinal air 125 passage 19^a. Besides providing for the use- 130

ful air space the blocks more readily adapt themselves automatically to any slight roughness that may exist in the floor support. The strength or necessary stiffness of the floor, however, is not materially impaired by this reduction in thickness of the central part of each block.

While I refer specifically herein to interlocked flooring it is to be distinctly understood that my interlocking blocks as structural units may be employed in various other relations, and hence I do not propose to be limited unnecessarily in the scope of the claims to any specific art in the practice of the invention.

I claim:

1. The herein described floor block having straight ends and edges, one end having an unbroken tongue, while the other end has a groove adapted to receive a tongue of the endwise adjacent block, the front edge of the block having a plurality of spaced dovetailed tongues, one of the tongues constituting an integral extension of the aforesaid end tongue, and the rear edge of the block being provided with dovetailed grooves that are the counterpart of the front edge tongues and between the dovetailed grooves said rear edge is provided with a plurality of mortises the cross section of which is larger than the cross section of the tongues and grooves.

2. The herein described floor block having straight ends and edges, one end having an unbroken tongue, while the other end has a groove adapted to receive a tongue of the endwise adjacent block, the front edge of the block having a plurality of spaced dovetailed tongues, one of the tongues constituting an integral extension of the aforesaid end tongue, and the rear edge of the

block being provided with dovetailed grooves that are the counterpart of the front edge tongues, one of which grooves is midway of the length of said block, and between the dovetailed grooves said rear edge is provided with a plurality of mortises the cross section of which is larger than the cross section of the tongues and grooves.

3. The herein described floor block having straight ends and edges, one end having an unbroken tongue, while the other end has a groove adapted to receive a tongue of the endwise adjacent block, the front edge of the block having a plurality of spaced dovetailed tongues, one of the tongues constituting an integral extension of the aforesaid end tongue, and the rear edge of the block being provided with dovetailed grooves that are the counterpart of the front edge tongues and between the dovetailed grooves said rear edge is provided with a plurality of mortises the cross section of which is larger than the cross section of the tongues and grooves, said mortises having rounded ends.

4. The herein described interlocking block for a building unit, the same having a smooth flat upper surface and straight parallel edges, one of the edges of the block being provided with a pair of spaced mortises on opposite sides of the center of the edge, the mortises having rounded ends and otherwise flat bounding walls, the same edge having a plurality of aligned dovetailed grooves leading from the ends of the mortises, and the opposite edge of the block having a plurality of dovetailed tongues constituting the counterparts of the dovetailed grooves.

JACOB D. BUTLER.
